Primary Examiner — T Chase Nelson(74) Attorney, Agent, or Firm — Shook, Hardy and Bacon L.L.P.(57) CLAIM

The ornamental design for a shoe, as shown and described.

DESCRIPTION

FIG. 1 is a bottom plan view of a shoe showing my new design;

FIG. 2 is a front perspective view thereof; and,

FIG. 3 is a rear perspective view thereof.

The even-length broken lines are directed to environment, represent unclaimed subject matter, and form no part of the claimed design.

The long-and-short broken lines immediately adjacent shaded areas form an unclaimed boundary, and form no part of the claim.
